UNITED STATES PATENT OFFICE.

EDWARD P. DONNELLAN, OF BROOKLYN, NEW YORK, ASSIGNOR, BY MESNE ASSIGNMENTS, TO STANDARD-JOHNSON CO., INC., A CORPORATION OF NEW YORK.

WRAPPER-HOLDING MECHANISM FOR COIN-COUNTING MACHINES.

1,406,623.

Specification of Letters Patent. Patented Feb. 14, 1922.

Application filed November 30, 1920. Serial No. 427,389.

To all whom it may concern:

Be it known that I, EDWARD P. DONNELLAN, a citizen of the United States, residing at Brooklyn, in the county of Kings and 5 State of New York, have invented certain new and useful Improvements in Wrapper-Holding Mechanism for Coin-Counting Machines; and I do hereby declare the following to be a full, clear, and exact description 10 of the invention, such as will enable others skilled in the art to which it appertains to make and use the same, reference being had to the accompanying drawings, and to characters of reference marked thereon, which 15 form a part of this specification.

The present invention relates, generally, to improvements in coin-counting machines; and the invention has reference, more particularly, to an improved mechanism for 20 holding wrappers subject to the delivery thereinto of coins from the coin counting and delivery mechanism.

The invention has for its principal object to provide a novel construction of wrapper holding mechanism for coin counting machines more particularly designed for the rapid handling of the coins delivered by the latter, and at the same time providing means for quickly locating and positioning the wrappers when the same are inserted in the tubular holders therefor, and also for automatically releasing the stop devices of the counting mechanism as the tubular holders are alternately brought into 25 operative relation to the coin counting and delivery mechanism. To these and other ends my present invention consists of a pair of tubular wrapper holders arranged in connection with a shiftable carrier device so that while one wrapper holder is in service the other is out of service, consequently permitting the removal of the coin filled wrapper from and the insertion of a new wrapper in the latter while the coins are filling the 30 wrapper supported by the former; and the invention further consists of adjustable means for cooperation with the wrapper holders when out of service which will determine the correct position of the wrappers 35 when inserted therein; and the invention also consists of means for automatically producing a preliminary crimp at the bottom of the wrapper as the tubular holders supporting the same are moved into service position. The invention also provides a means

operated through the movement of the shiftable carrier device for releasing the automatic stops of the coin counting means to permit renewed operation of the counting and delivery mechanism each time a tubular 60 holder is moved into service position.

Other objects of the invention, not at this time more particularly enumerated will be clearly understood from the following detailed description of the same.

With the various objects of the invention in view, the same consists, primarily in the novel wrapper holding mechanism for coin counting and delivery machines hereinafter set forth; and the invention consists, furthermore, in the novel arrangements and combinations of several devices and parts, as well as in the details of the construction thereof, all of which will be hereinafter more fully described and then embodied 70 in the appended claims.

The invention is clearly illustrated in the accompanying drawings, in which:—

Figure 1 is a front elevation of a portion of a coin counting machine provided with 80 the novel wrapper holding mechanism made according to and embodying the principles of the present invention; Figure 2 is a plan view of the same; Figure 3 is a detail vertical longitudinal section through the same, 85 taken on line 3—3 in said Figure 2; and Figure 4 is a detail horizontal section taken on line 4—4 in said Figure 1.

Similar characters of reference are employed in all of the hereinabove described 90 views, to indicate corresponding parts.

Referring now to said drawings, the reference character 1 indicates a coin counting machine of the type and general construction shown and described in prior Letters 95 Patent of the United States, No. 1,160,830, dated November 16th, 1915, the same comprising a suitably supported bed-plate 1 with which is associated a rotatable table 2, the marginal portions of which are surrounded by a coin guiding and controlling means 3. A rotatable propeller wheel 4 is mounted upon said bed-plate 1 to receive the coins delivered from said coin guiding and controlling means 3, so as to engage said 100 coins and successively propel the same into actuating engagement with the star wheel 5 of a coin counting mechanism 6, and then finally deliver the same to the wrapper holding mechanism. Said coin counting 110

mechanism is, in its detail construction, the same as described in said above-mentioned prior patent, and is provided with a pivoted stop controlling bar 7, which controls the 5 stops for automatically locking the coin counting mechanism when the desired predetermined number of coins have been counted and delivered to and deposited in the wrapper arranged and supported to receive the 10 same.

The novel wrapper holding mechanism, which is the subject of the present invention, comprises a laterally disposed guide plate 8 having at its sides suitably formed 15 guide portions 9 with which a slide-plate 10 is movably engaged. Said guide plate 8 is provided with a chute member 11 terminating at its forward end in a delivery opening 12. Surrounding the forward portion 20 of said chute member 11 is an upstanding guard wall 13 from each side of which project, in opposite directions, wings or lugs 14 which are positioned against the forward edge of said bed-plate 1, and through 25 which pass into said bed-plate fastening screws 15 for securing said guide plate 8 in fixed relation to said bed-plate 1, and so that the chute-member 11 is properly aligned to receive the coins as they are propelled forward after actuating the coin 30 counting mechanism. Said slide-plate 10 is provided with a pair of longitudinally spaced apart vertical openings or passages 16, and connected with the under side of 35 said slide-plate in alinement with said openings are depending bosses 17 having receiving sockets 18 in their lower free ends. The reference character 19 indicates tubular wrapper holders the upper ends of 40 which are respectively receivable in said receiving sockets 18, and are secured against displacement by set-screws 20 which screw through the walls of said sockets 18. The lower ends of said tubular wrapper holders 45 are open so that cylindrically shaped tubular wrappers 21 may be inserted thereinto so as to be embraced and held in place thereby.

Connected with said guide-plate 8, so as 50 to extend downwardly from the underside thereof, is a vertical hanger arm 22. Supported by said hanger arm 22, in a suitable location, are oppositely projecting lateral arms or bracket portions 23, to the free end 55 of each of which is an adjustable supporting block 24 capable of rotative adjustment relative to the ends of said bracket portions 23, said supporting blocks 24 being secured in desired adjusted positions by the set 60 screws 25 carried thereby. Adjustably mounted in connection with each supporting block 24 is a transverse carrier arm 26, adapted to be secured in desired adjusted position by means of the set-screws 27 connected with the outer ends of said support-

ing blocks 24. The forward free ends of said transverse carrier arms 26 are provided with laterally projecting stop pins 28, which extend toward the respective wrapper holders 19. Said wrapper holders 19 70 are provided in their outer side walls with upper openings 29 and lower openings 30, which at proper times permit the entrance therethrough of the stop pins 28, so that the latter project into the interior of the 75 wrapper holders 19 and serve as stops for arresting the tubular wrappers 21, when the latter are inserted in the said wrapper holders, thus determining the operative position of said wrappers in the holders. When the 80 carrier arms 26 are adjusted to position the stop pins 28 in alinement with the upper openings 29, the stop pins 28 serve to determine the position of full length or full capacity wrappers in the holders 19, but 85 when the carrier arms 26 are adjusted to position the stop pins 28 in alinement with the lower openings 30, the stop pins 28 serve to determine the position of half length or half capacity wrappers in the 90 holders 19. Adjustment of the stop-pins 28 for the latter relation may be accomplished by pulling forward the carrier arms 26 and then turning forward the supporting blocks 24 to lower the free ends of the 95 carrier arms to points opposite the lower openings 30 so as to bring said stop-pins opposite said openings.

Connected with the lower free end of said hanger arm 22, by means of suitably arranged and interconnected supporting arms 31, 32 and 33, is a crimping member 34 the shank 35 of which extends through the arm 33, so as to be vertically adjustable relative thereto for the purpose of locating the 105 crimping member 34 at a proper height, a set screw 36 being provided to secure the same in the desired adjusted position. When properly adjusted said crimping member 34 is positioned at a point immediately beneath and alined with the wrapper holder 19 occupying its "in service" position. 110

Connected with said coin counting mechanism, so as to be vertically movable in a 115 fixed guide means 37, is a trip bar 38 having at its lower end an anti-friction roller 39. Fixed on said slide-plate 10 is a cam member 40 having upwardly converging sides which, when passed beneath said trip bar in either direction, lifts the latter to cause a tripping of the stop controlling bar 7 of the coin counting mechanism to thereby release said coin counting mechanism for further operation. 120

The means for reciprocating the slide-plate 10 comprises a hand lever 41 which is pivotally connected by its rearward end to a convenient point at the under side of said bed-plate 1. The forward end of said hand 130

lever 41 extends through an opening 42 provided in said cam member 40, whereby a swinging movement of said hand lever in a horizontal plane in one direction or the other 5 will cause a sliding movement of said slide-plate 10 in a corresponding direction so as to position one or the other of said wrapper holders in a service position while the remaining wrapper holder is in out of service 10 position.

It will be apparent from an inspection of the drawings that the tubular wrapper holders 19 are detachable relative to the slide-plate 10, so that the same may be made in 15 different diameters according to the size of the coin operated upon in any given case. As shown in said drawings the tubular wrapper holders are of a size adapted to accommodate coins of the ten cent denomination, and the same are provided with enlarged upper ends 19' to fit the receiving sockets 18. Said receiving sockets 18 are of a 20 diameter large enough to receive wrapper holders of a diameter accommodating the largest size of coin, and the smaller and intermediate sizes of wrapper holders adapted to the smaller and intermediate sizes of coins, are all provided with said enlarged ends 19' to fit said receiving sockets 18.

30 In order to render clear the operation and manner of using the novel wrapper holding mechanism I have in Figure 1 of the drawings designated one wrapper holder 19 with the additional reference character X and its 35 fellow with the additional reference character Y. When the parts are actuated to occupy the positions shown in said Figure 1 the wrapper holder X occupies an "in service" position while the wrapper holder Y 40 occupies an "out of service" position. The coin counting mechanism is set so that, for example, fifty coins of the ten cent denomination will be counted and delivered through the chute member 11 and delivery opening 12 45 to be deposited in the wrapper 21 carried by the holder X, and then the counting mechanism stops until the automatic stop devices are released by actuation of the stop releasing bar 7. While the coins are being 50 delivered to the wrapper in the holder X, the holder Y being moved to the left to occupy an "out of service" position is operatively associated with the left hand carrier arm 26 and its stop pin 28 so that the latter 55 enters through the upper opening 29 of said wrapper holder Y. The operator thereupon thrusts into the lower end of said holder Y a paper wrapper 21, moving the same upwardly until it is stopped against the said 60 stop-pin 28, in which position the lower end of said wrapper 21 projects for a short distance downwardly beyond the end of said holder Y. When the counted coins have 65 been deposited in the wrapper supported by the holder X, the operator grasps the hand

lever 41 and swings the same to the right, thereby sliding to the right the slide plate 10. This movement of the slide-plate 10 carries the holder X with its coin filled wrapper to an "out of service" position, and at the 70 same time carries the holder Y to an "in service" position. As said holder Y moves to "in service" position, the lower projecting end of the wrapper 21 inserted therein is carried against the crimping member 34, 75 contact with which forms an initial crimp in the lower end of the wrapper tending to close the same against the escape of coins therefrom. In moving the slide-plate 10 to the right, the cam member 40 rides beneath 80 the trip-bar 38 imparting a lifting movement thereto which causes the stop controlling bar 7 to swing upward to release the automatic stops of the coin counting mechanism, so that operation of the latter mechanism will be resumed and continued until fifty coins have been deposited in the wrapper supported by said holder Y. In the meantime the holder X being in "out of service" position, the same is operatively 85 associated with the right hand carrier arm 26 and its stop-pin 28, so that the latter projects into the same through its upper opening 29, and consequently while the filling of the wrapper in the holder Y is taking place, 90 the operator may remove the filled wrapper from the holder X to finish the closing of the ends of the wrapper, and then insert a new wrapper into said holder X until stopped against said stop-pin 28. When the 95 wrapper in the holder Y is filled, the operator swings the hand lever 41 to the left, which moves the slide plate 10 in a corresponding direction, so that the holder Y is returned to "out of service" position, and the 100 holder X is returned to "in service" position, and the cam member 40 caused to actuate the trip bar 38 and stop controlling bar 7 to again start the coin counting and delivery mechanism. In this manner it will be apparent, that by a simple manipulation the respective holders X and Y are alternately carried into "in" and "out of service" positions, so that the operation of the machine 105 is rendered for all practical purposes continuous, and much time is saved, especially when the novel wrapper holding mechanism is used in connection with power driven counting machines.

I am aware that some changes may be 110 made in the general arrangements and combinations of the various devices and parts, as well as in the details of the construction thereof, without departing from the scope of the invention as set forth in the foregoing specification, and as defined in the appended claims. Hence, I do not limit my invention to the exact details of the construction of said devices and parts as described in said specification, nor do I con- 115 120 125 130

fine myself to the exact details of the construction of the said parts as illustrated in the accompanying drawings.

I claim:—

- 5 1. A wrapper holding mechanism for coin
counting machines, comprising a pair of tubular wrapper holders, means for alternately
moving said wrapper holders to an "in
10 service" position, and wrapper positioning
stops with which said holders cooperate
when in an "out of service" position.

2. A wrapper holding mechanism for coin
counting machines, comprising a pair of tubular wrapper holders, means for alternately
15 moving said wrapper holders to an "in
service" position, a wrapper-end crimping
member with which said holders cooperate
when in an "in service" position, and wrap-
20 per positioning stops with which said holders
cooperate when in an "out of service" posi-
tion.

3. The combination with a coin counting
machine having counting mechanism stops
25 and a releasing bar controlling said stops of
a wrapper holding mechanism, comprising a
pair of tubular wrapper holders, means for
alternately moving said wrapper holders to
30 an "in service" position, and means operated
by the movement of said holders for actuat-
ing said releasing bar controlling said count-
ing mechanism stops.

4. The combination with a coin counting
machine having counting mechanism stops
35 and a releasing bar controlling said stops
of a wrapper holding mechanism, comprising
a pair of tubular wrapper holders, means for
alternately moving said wrapper holders to
40 an "in service" position, means operated
by the movement of said holders for actu-
ating said releasing bar controlling said
counting mechanism stops, and wrapper po-
sitioning stops with which said holders co-
50 operate when in "out of service" position.

5. The combination with a coin counting
45 machine having counting mechanism stops
and a releasing bar controlling said stops of
a wrapper holding mechanism, comprising
a pair of tubular wrapper holders, means for
55 alternately moving said wrapper holders to
an "in service" position, means operated by
the movement of said holders for actuating
said releasing bar controlling said counting
mechanism stops, and a wrapper-end crimp-
60 ing member with which said holders coop-
erate when in an "in service" position.

6. The combination with a coin counting
65 machine having counting mechanism stops
and a releasing bar controlling said stops of
a wrapper holding mechanism, comprising
a pair of tubular wrapper holders, means for
alternately moving said wrapper holders to
70 an "in service" position, means operated by
the movement of said holders for actuating
said releasing bar controlling said counting
mechanism stops, a wrapper-end crimping

member with which said holders cooperate when in an "in service" position, and wrapper positioning stops with which said holders cooperate when in "out of service" position.

7. A wrapper holding mechanism for coin 70
counting machines, comprising a guide-plate
having a chute member terminating in a de-
livery opening, a slide-plate supported by
said guide-plate having openings registrable
with said delivery opening, a pair of tubu- 75
lar wrapper holders, means for supporting
said holders in alinement respectively with
said slide-plate openings, means for recipro-
cating said slide-plate to alternately move
said holders into "in service" position rela- 80
tive to said delivery opening of said guide-
plate, a fixed hanger arm, wrapper position-
ing stop-pins, adjustable means carried by
said hanger arm for supporting said stop-
pins, and said holders having openings 85
through which a stop-pin projects when said
holders occupy an "out of service" position.
8. A wrapper holding mechanism for coin
counting machines, comprising a guide-plate
having a chute member terminating in a de- 90
livery opening, a slide-plate supported by
said guide-plate having openings registrable
with said delivery opening, a pair of tubu-
lar wrapper holders, means for supporting
said holders in alinement respectively with
said slide-plate openings, means for recipro- 95
cating said slide-plate to alternately move
said holders into "in service" position rela-
tive to said delivery opening of said guide-
plate, a fixed hanger arm, wrapper position-
ing stop-pins, adjustable means carried by
said hanger arm for supporting said stop-
pins, and said holders having openings 100
through which a stop-pin projects when said
holders occupy an "out of service" position,
a crimping-member, and adjustable means
carried by said hanger arm for supporting
said crimping member in operative relation
to said holders when the latter occupy an 105
"in service" position.
9. A wrapper holding mechanism for coin
counting machines, comprising a guide-plate
having a chute member terminating in a de- 110
livery opening, a slide-plate supported by
said guide-plate having openings registrable
with said delivery opening, a pair of tubu-
lar wrapper holders, means for supporting
said holders in alinement respectively with
said slide-plate openings, means for recipro- 115
cating said slide-plate to alternately move
said holders into "in service" position rela-
tive to said delivery opening of said guide-
plate, a fixed hanger arm, a crimping-mem-
ber, and adjustable means carried by said 120
hanger arm for supporting said crimping
member in operative relation to said holders
when the latter occupy an "in service" pos-
ition.

10. The combination with a coin counting machine having counting mechanism stops 130

and a releasing bar controlling said stops of a wrapper holding mechanism, comprising a guide plate having a chute member terminating in a delivery opening, a slide-plate supported by said guide-plate having openings registrable with said delivery opening, a pair of tubular wrapper holders, means for supporting said holders in alinement respectively with said slide plate openings, means for reciprocating said slide plate to alternately move said holders into "in service" position relative to said delivery opening of said guide-plate, a vertically reciprocable trip-bar for actuating said releasing bar controlling said counting mechanism stops, and a cam carried by said slide-plate to actuate said trip-bar.

5 11. The combination with a coin counting machine having counting mechanism stops and a releasing bar controlling said stops of a wrapper holding mechanism, comprising a guide plate having a chute member terminating in a delivery opening, a slide-plate supported by said guide plate having 20 openings registrable with said delivery opening, a pair of tubular wrapper holders, means for supporting said holders in alinement respectively with said slide plate openings, means for reciprocating said slide plate 25 to alternately move said holders into "in service" position relative to said delivery opening of said guide-plate, a vertically reciprocable trip-bar for actuating said releasing bar controlling said counting mechanism 30 stops, a cam carried by said slide-plate to actuate said trip-bar, a fixed hanger arm, wrapper positioning stop-pins, adjustable means carried by said hanger arm for supporting said stop-pins, and said holders having openings through which a stop-pin projects when said holders occupy an "out of 35 service" position.

12. The combination with a coin counting machine having counting mechanism stops and a releasing bar controlling said stops of a wrapper holding mechanism, comprising a guide plate having a chute member terminating in a delivery opening, a slide-plate supported by said guide-plate having openings registrable with said delivery opening, a pair of tubular wrapper holders, means for supporting said holders in alinement respectively with said slide plate openings, means for reciprocating said slide plate to alternately move said holders into "in service" position relative to said delivery opening of said guide-plate, a vertically reciprocable trip-bar for actuating said releasing bar controlling said counting mechanism stops, a cam carried by said slide-plate to actuate said trip-bar, a crimping-member, and adjustable means carried by said hanger arm for supporting said crimping member in operative relation to said holders when the latter occupy an "in service" position.

40 13. The combination with a coin counting machine having counting mechanism stops and a releasing bar controlling said stops of a wrapper holding mechanism, comprising a guide plate having a chute member terminating in a delivery opening, a slide-plate supported by said guide plate having openings registrable with said delivery opening, a pair of tubular wrapper holders, means for supporting said holders in alinement respectively with said slide plate openings, means for reciprocating said slide plate to alternately move said holders into "in service" position relative to said delivery opening of said guide-plate, a vertically reciprocable trip-bar for actuating said releasing bar controlling said counting mechanism stops, a cam carried by said slide-plate to actuate said trip-bar, a crimping-member, and adjustable means carried by said hanger arm for supporting said crimping member in operative relation to said holders when the latter occupy an "in service" position.

In testimony, that I claim the invention 90 set forth above I have hereunto set my hand this 26th day of November, 1920.

EDWARD P. DONNELLAN.
